UNITED STATES PATENT OFFICE.

HENRY TESSEYMAN, OF DAYTON, OHIO, ASSIGNOR TO THE BARNEY AND SMITH CAR COMPANY, OF DAYTON, OHIO, A CORPORATION OF WEST VIRGINIA.

METALLIC UNDERFRAME FOR RAILROAD-CARS.

No. 893,282.

Specification of Letters Patent.

Patented July 14, 1908

Application filed January 20, 1908. Serial No. 411,746.

To all whom it may concern:

Be it known that I, HENRY TESSEYMAN, a citizen of the United States, and a resident of the city of Dayton, in the county of Montgomery and State of Ohio, have invented certain new and useful Improvements in Metallic Underframes for Railroad-Cars; and I do hereby declare the following to be a full, clear, and exact description of the invention, such as will enable others skilled in the art to which it appertains to make and use the same, reference being had to the accompanying drawings, and to the numerals and letters of reference marked thereon, as forming a part of this specification.

My invention relates to metallic underframes for railroad cars; and has for its objects to provide an improved and simple construction thereof whereby additional strength is contributed to such structures, and whereby greater convenience in building and repairing the same is attained and the expense thereof reduced.

The invention consists in the novel and convenient construction and arrangement of the various parts forming the structure, as hereinafter fully described, and shown in the accompanying drawings, and which are clearly pointed out in the claims at the end of this specification.

In the said drawings:—Figure 1 is a broken perspective view of the under-frame showing the drawbar in its position therein and the arrangement of the several features covering my improvements; Fig. 2 a broken perspective view of the draw-bar buffer casting; Fig. 3 a broken perspective view of the draw-bar carry-iron; Fig. 4 a perspective view of the buffer reinforce casting; Fig. 5 a cross-sectional view of the side sill as applied to coal cars and showing a stake for supporting the side walls thereof; Fig. 6 a broken side elevation of Fig. 5; Fig. 7 a cross-sectional view of the side-sill as applied to box cars; Fig. 8 a cross-sectional view of the side-sill as applied to flat cars; Fig. 9 a broken perspective view of the connecting casting to which the draft-sills, the bolster and the center-sill are rigidly connected and which when so connected form a single structure, and Fig. 10 is a broken plan view showing the manner of connecting the center-casting

with the bolster and center-sill, Figs. 2 to 10 inclusive being of larger scale than Fig. 1.

While in the drawings (Fig. 1) but one end of the under-frame is represented it is to be understood that both ends thereof are alike, therefore, in describing the invention separate reference to such parts as are duplicated at the opposite end will not be necessary, and it is to be further understood that in making and assembling the various parts any desirable means usual in such practice, may be employed for securing the same in their respective places.

In the said drawings similar reference letters and numerals indicate corresponding parts in all the figures thereof.

A represents the center-sill, which is made in the form of a box-girder comprising two side-channels, 1 and 1^a spaced a suitable distance apart and connected together by upper and lower plates 2 and 2^a.

B is a bolster and sill connecting-block comprising a casting of such form and so strengthened by ribs and flanges as to produce the requisite amount of strength with a minimum amount of material and which is provided, at its center, with an integrally formed hollow sleeve 3, through which passes the usual king-bolt, not shown, and which is further provided with wings 4—4^a; 5—5^a; 6—6^a; 7 and 7^a, this casting constitutes a part of the bolster, designated as C and which, like the center-sill, is made up of side-channels 8 and 8^a, there being four channels to each bolster, spaced a suitable distance apart and secured together by upper and lower plates 9 and 9^a, at opposite sides of the casting B, these side-channels are secured to the wings 4—4^a and 7—7^a of the said casting while the upper and lower plates, 9—9^a, extend across the said casting the entire length of the bolster and are secured to side-sills, D, D, by means of angle-pieces, one of which is shown at E, Fig. 1, and suitable bolts or rivets. The channels 1—1^a of the center sill A extend from bolster to bolster, their ends being secured to the wings 6—6^a of the casting B; while the upper and lower plates, 2—2^a, extend across and beyond the said casting and are secured to the flanged portions of channels 10 and 10^a which constitute draft sills, the rear ends of which are secured

to the wings 7—7^a of said casting, and thus the center sill, bolster and draft sills when assembled and united as above described constitute a single structure of great strength 5 and efficiency, besides being extremely advantageous in the construction of the under-frame and in making repairs thereto.

The side sills D are each composed of two Z bars, 11—12, so secured together as to 10 form a channel on the inside, and a double, longitudinal, flange or shelf on the outside upon which rests a timber E which is fastened to the Z bar 11 and to which the floor F, siding G, and any desirable frame-work 15 extending above the floor may be secured; and to which, in coal cars the stake-sockets H, carrying stakes I may be secured, this simple and inexpensive manner of constructing the side-sills, coupled with additional 20 strength contributed by the double, longitudinal, flanges at the center avoids the necessity of securing to the sill an additional longitudinal shelf or rest for the timber E and provides a most desirable structure for 25 the purposes intended.

J represents the end-sills, to which the side-sills and the draft-sills are united, angle-pieces (shown in Fig. 1, by dotted lines) being employed in making the union of these 30 parts, and the frame being braced by suitable brace-members which extend from the outer corners of the same to points where the bolster and draft-sills meet.

At or about the center of the end-sill its 35 lower flange and a part of its web are cut away to form an opening to receive the draw-bar 13 of the draft-rigging L, the draw-bar being supported by the usual carry-iron M, secured at its outer-ends to the lower flange 40 of the channel constituting the end-sill and, intermediately, by bolts which pass through the upper and lower flanges of the said channel through recesses 14—14^a, formed in a buffer-casting N, located between the flanges of 45 said channel and secured thereto for the purpose of contributing strength to the structure at this point; the lower portion of this casting being cut-away to register with the opening formed in the end-sill to receive the draw-bar. A re-inforce casting O is located above 50 the draw-bar and secured to the draft-sills, preferably by rivets, and to the end-sill by bolts which pass therethrough and through the said buffer-casting, and thus additional 55 strength is contributed to the structure.

To the inside of each of the draft-sills there are secured a pair of draft-lugs 15—15^a, between which are located buffer-follower-plates 16—16^a and buffer-spring 17 which 60 constitute a part of the draft-rigging, the function of the lugs 15 being to receive the draft strains and that of the lugs 15^a to receive the buffing strains, the latter mentioned lugs, in addition to being secured to the

draft-sills, are butted against projections 18, 65 preferably cast integral with the casting-block B, which, to a considerable extent relieve the bolts or rivets, by which the lugs are secured to the draft-sills, from the buffing shocks and more thoroughly transmit the 70 same through the casting B to the center-sill and thence through the entire length of the under-frame.

From the foregoing it will be observed that an essential feature of my invention lies in 75 the novel construction of the body-bolster and the manner in which the draft-sills and the center-sill are connected therewith to form a single structure and the convenient arrangement of all the parts whereby same 80 can be removed without disturbing others, which as hereinbefore stated is of great advantage, not only in the construction of new work but also in making repairs, also that the buffer-casting can be removed and replaced 85 independently of and without disturbing any of the other parts of the structure.

It is obvious also that the details of construction may be departed from in various ways without departing from the spirit of 90 my invention and, therefore, I do not limit the invention to the exact details which I have illustrated and described herein.

Having thus fully described my invention, what I claim and desire to secure by Letters 95 Patent, is—

1. In a metallic under-frame, a bolster composed of a plurality of sections comprising a pair of channels spaced apart and connected by upper and lower plates, a connecting-block intermediate the said sections and secured thereto, in combination with means for connecting draft-sills and a center-sill with said connecting-block. 100

2. In a metallic-under-frame, the combination with side-sills, of channel-shaped end-sills, drawer-bars located and operating in openings formed by cutting away a portion of the webs and lower flanges of said channel-shaped end-sills, buffer-castings located between the flanges which form the channel-shaped end-sills and which are secured to the latter adjacent to the openings for the draw-bars therein, draw-bar carry-irons secured to the said lower flanges of the end-sills below 110 said openings, and recesses formed in said buffer-castings for the passage of bolts from the upper flanges of said end-sills to and through the lower flanges thereof and through said carry-irons. 115

3. In a metallic under-frame, the within described buffer-casting having the recesses formed therein for the passage of bolts therethrough and provided with a suitable passage-way for the reception and operation of a 120 draw-bar.

4. In a metallic under-frame, the combination of side-sills and end-sills, with draft-

sills located between the side-sills, draw-bars located between the draft-sills, buffer-castings secured to the end-sills, and reinforce-castings located at the back side of the end-sills above the draw-bars and secured to the draft-sills and end-sills.

5. In a metallic under-frame, the within described side-sills each comprising a plurality of **Z** bars secured together so as to form a longitudinal shelf or bearing on the outside thereof, in combination with a timber-piece resting thereon and secured to the side-sill

and constituting a member to which may be secured the floor and upper frame-work of the car, and end-sills to which the side-sills are 15 connected.

In testimony that I claim the foregoing as my invention I hereunto subscribe my name in the presence of two subscribing witnesses this 17th day of January, 1908.

HENRY TESSEYMAN.
